HAIR CURLER

Nathan Lewis Solomon, Brooklyn, N. Y.

Application December 21, 1936, Serial No. 117,072

5 Claims. (Cl. 132—41)

The present invention is generally concerned with hair curlers wherein swingably connected complementary clamping components in the form of a tube and cover serve in the dual capacity of hair gripping means and hair rolling means. In a specific aspect the invention is particularly concerned with an improved means for curling hair wherein one of the components of the curler is also employed as a foraminous magazine adapted to advantageously and removably receive a cartridge or insert carrying a suitable exothermically operating chemical composition adapted to react with an appropriate liquid reagent to generate heat which is directed to hair exteriorly wound about the complements. In another aspect, the invention is realized in the provision of a simplified hair curling device comprising fulcrum means pivotally sustaining a perforated tube and cover the latter serving to conveniently receive a chemically heat producing cartridge while the fulcrum means cooperates to limit insertion of the cartridge within the tube. As another aspect of the invention the fulcrum means swingably supports a loop having sides adapted to hold the coiled hair about the tube and cover and is provided with a spheroidal resilient stay which cooperates with one end of the tube to hold the loop in a set position and also cooperates with an adjacent end of the cartridge to yieldingly sustain the latter within the tube and against longitudinal displacement relative to the curling device.

With the above and other objects in view, the invention further resides in the details of construction and arrangement of parts hereinafter more specifically pointed out in the following detailed description of the accompanying drawing in which:—

Fig. 1 shows a perspective view of the improved curler according to my invention.

Fig. 2 is an enlarged sectional view taken along the line 2—2 of Fig. 1.

Fig. 3 is a broken perspective view of the heat generating insert or cartridge according to the invention.

Fig. 4 is an enlarged longitudinal sectional view of the curler illustrated in Figs. 1 and 2.

Fig. 5 is a sectional view taken on the line 5—5 of Fig. 4.

Fig. 6 is a sectional view taken on the line 6—6 of Fig. 4.

Fig. 7 is a front but reduced elevational view of the protective guard, showing the hinged flap in a closed position and

Fig. 8 is a transverse sectional view of the pro-

tective guard illustrating the swingable flap in an open position.

The hair curler 10 embodies a perforated tube 11, a perforated cover 12, a swingable loop 13, a stay 14, and a heat generating cartridge 15. 5 Tube 11 and the superimposed cover 12 are pivotally sustained by fulcrum means in the form of a transversely disposed ferrule or tube 16 which has its outer terminals appropriately upset to prevent transverse displacement of the cover 10 relative to the tube.

The sides 17 of the loop each include a terminal 18 having an offset end or lip 19 cooperating with an associated upset portion 20 of the ferrule 16 to prevent accidental displacement of 15 a respective terminal 18 longitudinally of the ferrule. When disposed within the bore of the ferrule terminals 18 are in abutting overlapping relation closely but rotatably confined therein.

The tube and cover each include a finger manipulating portion 21 adapted to be held diverged by a substantially U shaped leaf spring 22 for normally holding the cover against the tube. 20

As illustrated, the cartridge 15 comprises a foraminous or perforated body 24 which may be 25 of aluminum or tin foil. This body may be rolled to take the form of a substantially cylindrical casing or package containing a suitable chemical, for example, calcium oxide 25, in granular or powdered form. The perforated or forami- 30 nous casing 24 has imperforate ends 26 to prevent lateral leakage of the powdered chemical therefrom and is provided with twisted ends 27 forming overhanging projections for a purpose hereinafter set forth. 35

Closely surrounding the exterior surfaces of the perforated metal foil casing 24 is a porous and absorbent interstitial jacket or sheath 28, preferably of cheesecloth or the like. This jacket readily absorbs water and readily acts to distribute its moisture through its length and into the perforations of the casing 24. Ties 29 which may be of string or wire encompass spaced portions of the porous jacket to hold the latter against the casing. 40

Before applying the curler to the hair to be curled, a composite pad or guard 30 is used to protect the head. This composite guard 30 preferably consists of a layer of rubber 31 to which is secured a layer of felt 32. The guard is provided with an inverted U shaped striation 33 defining a swingable flap 34. 45

In operation, a tress of hair to be treated is passed through opening 35 formed by pressing flap or closure 34 towards the head of hair. The 50 55

pad is moved against the head of hair and finger pressure on flap 34 is released. Thus the flap swings away from the head of hair and frictionally cooperates with the tress to prevent displacement thereof. With the resilient stay 14 disconnected from the tube 11 of the curler, the latter is opened upon the application of finger pressure to the manipulating portions 21 causing the latter to move towards each other. In such relation the cover and tube are separated forming a gap in which the terminal part of the tress is placed. Subsequently finger pressure is removed from manipulating portions 21 and the inserted terminal part of the tress is automatically clamped between the cover and tube due to the expansion of spring 27.

The curler is now bodily rotated about its longitudinal axis to take up the tress of hair threaded through the guard to form a plurality of superimposed convolutions. With the stay of the loop detached from the tube, the cartridge is immersed in a suitable reagent, such as water. Moisture therefore is collected by the interstitial netting or sheath 28 and drains into the casing 24 through its perforations, coming into intimate contact with the comminuted quick lime encased thereby. Following this step, the saturated cartridge is inserted in the tube of the curler until one projection 27 thereof strikes the transversely disposed fulcrum 16 which in this connection serves as a stop. The loop 13 is now swung to permit the compressible stay 14 to telescopically interlock with the outer end of the tube. During this action a portion of the rotatable stay 14 carried by the loop cooperates to deform an adjacent end 27 of the cartridge and therefore the latter is held against longitudinal displacement relative to the tube.

The chemical reaction between the calcium oxide and water, liberates a certain amount of heat and steam which passes through the perforations of the metal foil casing 24. This heat is also transmitted to the porous jacket 28 causing the moisture thereof to be turned into steam. The steam generated by the cartridge passes through the aligned perforations of the tube and cover of the curler. Thus the hair wound about these complementary hair gripping members is processed, that is, subjected to steam and subsequently dried, forming in fact a permanent wave. If desired, the tress threaded through the guard may be treated with a suitable chemical solution or water to enhance waving thereof when subjected to the exothermic action of the cartridge. Instead of using calcium oxide, other exothermically reacting chemical may be employed, for example, strontia, etc. Of course the types of chemical herein disclosed are merely illustrative but it is to be understood that the cartridge is adapted to contain a charge of dry chemicals adapted to generate heat if coming into intimate contact with water or suitable liquid reagent. The invention further contemplates the provision of chemical accelerators or decelerators to be combined with powdered chemicals of the type to enhance or retard the heat control of the latter as is well understood in the art.

Having completed the processing operation in the matter of subjecting the hair wound about the complements 11 and 12 to steam and heat, the stay is disconnected from the tube causing sides 17 thereof to free the processed tress, the curler is slightly opened by moving manipulating portions 21 towards each other, and the processed curl is removed from the curling device.

Thereafter flap 34 is manually swung towards the head permitting the processed curl to be conveniently projected or passed through the opening 35 whereby the guard may be conveniently removed from the head without disturbing the contour of the processed curl.

While the invention has been specifically described in detail, it is to be understood that it is not limited to the specific details described but is capable of other adaptations and modifications within the scope of the appended claims.

I claim:

1. In combination, a guard having a swingable portion normally disposed substantially in alignment with the body of said guard and adapted to be swung out of alignment therewith to form an opening to permit threading of a tress of hair therethrough to permit said tress to overhang an outside face of said guard, means for rolling said tress to provide a plurality of convolutions externally thereof, and exothermically operating means carried by said rolling means for subjecting said convolutions to steam and heat. 15

2. In combination, a guard having a swingable portion normally disposed substantially in alignment with the body of said guard and adapted to be swung out of alignment therewith to form an opening to permit threading of a tress of hair therethrough to permit said tress to overhang an outside face of said guard, foraminous means for rolling said tress to provide a plurality of convolutions externally thereof, and a moisture absorbing and steam and heat generating cartridge removably sustained by said rolling means for processing said convolutions. 25

3. In combination, a guard having a swingable portion normally disposed substantially in alignment with the body of said guard and adapted to be swung out of alignment therewith to form an opening to permit threading of a tress of hair therethrough to permit said tress to overhang an outside face of said guard, foraminous means for rolling said tress to provide a plurality of convolutions externally thereof, and a moisture absorbing and steam and heat generating cartridge removably sustained by said rolling means for subjecting said convolutions to steam and heat, said rolling means adapted to be detached from said convolutions for passing the latter through said opening to be independent of said guard. 40

4. In combination, a foraminous tube, a foraminous cover, means pivotally sustaining said tube and cover, a loop swingably associated with said tube and cover, a moisture absorbing cartridge having a perforated but impervious casing containing an exothermically operating body and comprising terminal portions, and a moisture absorbing and distributing sheath secured to said casing, said cartridge adapted to be inserted in said tube, said pivotally sustaining means cooperating with one of said terminal portions to limit longitudinal displacement of said cartridge in one direction, and means carried by said loop and adapted to be removably associated with one end 60 of said tube and cooperating with another of said terminal portions to prevent longitudinal displacement of said cartridge in an opposite direction relative to said tube. 65

5. In combination, a foraminous tube, a foraminous cover, means pivotally sustaining said tube and cover, a moisture absorbing cartridge having a perforated but impervious casing containing an exothermically operating body and comprising terminal projections, and a moisture absorbing 70

5 and distributing sheath secured to said jacket, said cartridge adapted to be inserted in said tube, said pivotally sustaining means cooperating with one of said projections to limit longitudinal displacement of said cartridge in one direction, and a rotatable and resilient stay carried by said loop

and adapted to be removably associated with one end of said tube and yieldingly cooperating with another of said projections to prevent longitudinal displacement of said cartridge in an opposite direction relative to said tube.

NATHAN LEWIS SOLOMON.
